UNITED STATES PATENT OFFICE.

ALBERT H. CARRIER, OF ASHEVILLE, NORTH CAROLINA.

CASEMENT-WINDOW ATTACHMENT.

Application filed September 28, 1921. Serial No. 503,813.

To all whom it may concern:

Be it known that I, ALBERT H. CARRIER, a citizen of the United States, residing at Asheville, in the county of Buncombe and 5 State of North Carolina, have invented new and useful Improvements in Casement-Window Attachments, of which the following is a specification.

This invention relates to casement window attachments, and the primary object of 10 the same is to provide means applied to and cooperating with a casement window frame and sash and readily actuated for positively opening and closing the sash and 15 holding the latter in fixed open adjustment at any angle desired for ventilating purposes, and also to permit the sash to turn or be shifted into such position that the outer side of the glass may be conveniently 20 cleaned from the inner side of the frame, without requiring an uncomfortable or dangerous position of the person performing the cleaning operation. A further object of the 25 invention is to provide an attachment of the class specified having a simplified and economically manufactured organization of parts and capable of being readily applied to casement window frames and sash at the time of the primal installation of the latter, 30 with materially reduced cost, particularly in window frame structures as sash weight boxings and sash weights are eliminated, and also capable of being easily applied to 35 casement windows and sash after erection of a window frame, without requiring any 40 material mutilation or cutting or boring of the adjacent lower and upper parts of the sash and frame to receive the cooperating 45 components of the complete attachment. A 50 further object of the invention is to provide an attachment for a casement window which will not only be effective as an operating means for readily opening and closing the sash, but also adapted to serve as a positive 55 locking means for the sash, particularly when the latter is closed, and thereby defeat any attempts to open the sash from the exterior of the casement window. A 60 still further object of the invention is to provide an opening and closing attachment for a casement window sash that is so positioned or applied and operable from the inner side of the frame and sash that the latter may be readily opened and closed

while a screen or analogous device applied 55 to the inner part of the frame remains in closed position, and which screen will at all times exclude the entrance of insects through the open casement.

With these and other objects and advantages in view, the invention consists in the preferred construction and arrangement of parts which will be more fully hereinafter described and claimed.

In the drawings:

Fig. 1 is a perspective view of a portion of a casement frame and sash, illustrating the sash as being open for ventilating purposes, and having the lower organization of the improved attachment applied thereto;

Fig. 2 is a transverse vertical section through a casement window frame and sash taken on the line 2—2, Fig. 5, and showing the sash closed and a screen at the inner part of the frame, the frame, sash and screen being broken through and the upper and lower organizations of the attachment illustrated in cross section;

Fig. 3 is a vertical section taken on the plane of the line 3—3, Fig. 5, through the lower organization of the attachment, the frame and sash being broken away and the sash illustrated in open position;

Fig. 4 is a top plan view of a part of the lower organization of the attachment, showing the actuating worm in horizontal section and a portion of the operating means thereof;

Fig. 5 is a top plan view of a portion of a casement frame and sash, the sash and part of the frame being shown in horizontal section, illustrating the lower attachment organization in full and dotted lines;

Fig. 6 is a section taken on the line 6—6, Fig. 5;

Fig. 7 is a detail perspective view of the swinging sash-engaging element of the lower organization of the attachment;

Fig. 8 is a perspective view of the main part or supporting member of the lower organization of the attachment;

Fig. 9 is a detail perspective view of the operating shaft or rod and its mounting, together with the worm and keeper plate for holding the worm in place in its seat;

Fig. 10 is a detail perspective view of the top member of the upper hinge organization of the attachment;

Fig. 11 is a detail perspective view of the sash-engaging member of the upper hinge organization of the attachment.

The numeral 5 designates a casement frame of a simple construction and comprising a sill 6 with a stool 7 projecting inwardly therefrom and an upper frame head 8. Within this frame a sash 9 is mounted to swing outwardly and inwardly through the medium of the improved attachment, which will be presently explained, and whereby the sash may be opened and closed by a very simple operation. The sash 9 is provided with glass or transparent panes 10 as usual, and in view of the pivotal mounting of the sash, the outer side of the glass may be readily reached for cleaning purposes without requiring an uncomfortable or dangerous position on the part 15 of the operator. The improved attachment is operative to adjust the sash at different angles as may be desired for ventilating purposes, or the sash may be entirely closed, and in the present instance the upper and lower parts of the attachment may be so disposed and operated as to provide an opening between the sash and the nearest upright or side member 11 of the casement frame, and whereby wind pressure will be materially relieved from the open sash and strain and injury to the latter reduced to a minimum by deflecting the air currents through the opening between the sash and the said adjacent upright member or frame. 20 By this means pocketing of air currents between the sash and frame is prevented. By disposing the parts of the attachment in the position explained, the sash may be swung to such angle that openings will be formed at opposite sides of the sash and a more thorough and satisfactory ventilation will ensue.

The improved attachment comprises a base supporting and securing member 12, a sash-engaging and attaching member 13 mounted to swing or have pivotal association with the base supporting member 12 and provided with a toothed quadrant 14. A worm or worm head 15 is operatively associated with the base supporting member 12 and held in mesh with the quadrant 14 for operating the latter, and removably engaging the said worm or head 15 is an operating rod or shaft 16, which is so constructed and arranged as to be easily rotated in opposite directions to actuate the sash attaching or pivotal member 13 through the medium of the said quadrant. It is proposed to proportion and relatively dimension the members 12 and 13 to reduce as much as practicable the amount of metal necessary in the construction of these members and also to bring them into close engaging relation, and thus reduce their extent vertically and longitudinally with re-

spect to the parts of the window frame to which they are secured. In addition to the base supporting member 12 and sash attaching member 13 pivotally associated therewith together with the operating worm or worm head 15 and operating rod or shaft 16, the attachment includes a pivotal or auxiliary fulcrum organization shown in detail by Figs. 10 and 11 and adapted to be interposed between the upper rail of the sash 9 and the head 8 of the casement frame 5. This auxiliary fulcrum attachment consists of a hinge or pivot plate 17 secured to the top rail of the sash and carrying an intermediately positioned stud 18, and a top hinge plate 19 which is secured in the lower portion of the head 8 of the frame 5 and provided with a socket 20 to removably receive the stud 18. All of the parts of the attachment are formed of metal, preferably of a non-corrosive character, and it is obvious that a material reduction in the cost of manufacture and sale price of the improved attachment will result if the amount of metal used in the construction of the attachment parts is reduced to a minimum without detracting from the necessary strength and durability of the improved attachment. It will therefore be understood that the size and dimensions of the members 12 and 13 and their cooperating parts, together with the auxiliary fulcrum attachment comprising the members 17 and 19 and their several structural features herein-after more particularly explained, will be adapted and modified in accordance with the dimensions and general proportions of the frame and casement window with which the attachment as a whole is operatively applied and used.

The members 12 and 13 also have a single intermediate hinge or pivot point which will be in vertical alignment with the intermediate hinge point of the top members 17 and 19, the intermediate positioning of the pivotal device of the upper and lower parts of the attachment giving the casement sash a positive opening action and movement away from the casement frame when the sash is shifted outwardly, and conversely, a movement of the sash towards the frame during the closing operation of the sash. In this particular construction of the casement attachment there is no sliding or displacing action of the pivotal points or elements of the upper and lower parts of the attachment, and it is proposed to utilize any suitable relatively cooperating means for providing a pivotal action between the parts of the attachment with the least possible friction and wear, and also to have the pivotal members or units for the upper and lower parts of the attachment of a simple and economically constructed character and capable of withstanding considerable strain without li-

ability of breakage. The preferred pivotaling parts cooperating therewith and proper devices of the upper and lower parts of the attachment also insure an easy operation of the sash at all times both in the opening and closing movements of the sash.

The specific construction of the base member 12 and the sash attaching member 13 together with the parts operatively associated therewith is clearly shown by Figs. 7, 8 and 9, and consists of a vertical cover plate 21 which is suitably attached to the sill 6 and let into the projecting outer edge of the stool 7, as shown by Figs. 1 and 5, the said cover plate having a vertical extent equal to the vertical extent of the edge or step 22 between the outer portion of the stool and the sill 6, as shown by Fig. 1. The maximum vertical extent of this cover plate 21 terminates at its inner portion coincident with an intermediate horizontal table 23 and has its outer surface flush with the outer side edge of the said table. From this table a stud or pivot boss 24 projects upwardly, and in the upper end of the said stud or pivot boss a socket 25 is formed, to receive an anti-frictional ball 26. The inner terminal of the table 23 is guarded by an upstanding flange or shield 27 of the form shown by Fig. 8, the inner end of the shield 27 being curved. Continuing from the inner terminal of the table 23 is a straight securing member 29 of comparatively reduced thickness and having a moisture collecting trough 30 at its inner portion, the outer wall 31 of this trough being formed with a transverse slot 32 therethrough, to permit drainage of the moisture collected in said trough exteriorly over the securing member 29 and the sill 6. This trough 30 also serves as an occluding means at the point of application of the member 12 to the sill and stool, by preventing moisture from entering the lower part of the frame and obviating deterioration or rotting of the frame structure, as shown by Figs. 6 and 8. Openings 33 are formed through the securing member 29 for the reception of fastenings adapted to engage the sill below or upon which the said securing member is applied. The outer extremity of the member 12 as shown by dotted lines in Fig. 5 has a flange 34 with apertured securing lugs 35, to receive suitable fastenings, the said flange 34 projecting inwardly from the cover or face plate 21 of the member 12. At the inner extremity of the member 12 a depending socket 36 is formed and is provided with an upper top plate extension or rest 37, for supporting a horizontally disposed cover plate 38 by means of suitable fastenings passing through openings 39 and 40 respectively formed in the plates 38 and 37. The socket 36 depends below the bottom of the securing member 29 and is disposed at a slightly oblique angle, as shown by Fig. 4, to give the work-

ing parts cooperating therewith a proper position relatively to the toothed quadrant 14, which moves over the socket. The upper edge of the socket opposite the top plate extension 37 is below the level of the top of the latter plate extension, and by this lower level of the socket edge an angle groove 41 is formed at this point in conjunction with the inner end of the securing member 29 and the moisture trough or receptacle 30, to provide for and operable disposition of the quadrant 14, so that the said quadrant will be at all times held operative relatively to the worm 15 over the top of the socket 36. The top of the socket is normally open and also the inner side, as at 42, the opening 42 at the inner side of the socket extending only partway downwardly in a vertical direction, and thus providing inner partial closing wall 43 opposite and outer closing wall 44 continuing upwardly to the top portion of the socket. The inner opening 42 is of less width than the socket, to thereby form angular retaining ribs 45 on opposite sides of said opening, the ribs extending downwardly to the lower minimized closed wall or side portion 43 of the socket. When the cover plate 38 is applied and secured to the top plate extension 37, the inner end of the said plate 38 projects over the top of the socket and also over the upper side of the quadrant 14 and serves to hold the latter in operative position to and in engagement with the worm or worm head 15, which is loosely disposed in the socket 36 and is free to rotate without jamming. In view of the oblique angular disposition of the socket 36, the worm or worm head 15 will be at all times held in practical working position relatively to the teeth of the quadrant 14, it being obvious that the teeth of the quadrant should have such contour as to easily mesh with the worm or worm head 15. The worm or worm head 15 has an enlarged angular socket 47 formed therein, to receive an operating head 48 on the outer end of the rod or shaft 16, the head being substantially square in contour and the socket 47 of a corresponding shape. The socket 47 is slightly larger than the head 48, so as to give ample play of the head without jamming in the socket for removable application of the rod or shaft 16 to the worm head 15, but at the same time a positive operating association of the head 48 with the worm head 15 is provided without lost motion, and thereby always insures a quick operative response of the worm head 15 to the actuation of the rod or shaft 16. The worm head 15 is retained in the socket by a vertical keeper plate 49 of the shape shown by Fig. 8 and having an enlarged square opening 50 therethrough, the opening 50 being of such dimensions that when the keeper plate 49 is inserted in the socket against the retaining

ribs 45, the head 48 on the outer end of the rod or shaft 16 may be inserted through the keeper plate in the socket 47 of the worm or worm head 15, and thus provide for a 5 very simple operation in assembling the shaft or rod with the worm or worm head. The keeper plate 49 is easily removable and also placeable in the rear portion of the socket and is formed with an upper notch 10 or slot 51, to give clearance to the quadrant 14, which moves thereover. The rod or shaft 16 may be as long as desired and in accordance with the base depth of the frame, the said shaft being disposed under the stool 15 7 and through the sill 6 in a suitable opening provided therefor in the base of the casement frame and also through an inner vertical finishing and supporting strip 52 of the frame. An escutcheon or plate 53 is secured 20 against the inner side of the strip 52 over the opening through which the rod or shaft 16 extends. The rod or shaft 16 has a sleeve head 54 secured on the inner end thereof and provided with spaced collars 55 and 56, which bear against the front and rear sides of the escutcheon or plate 53, as shown by Fig. 3, the head sleeve 54 extending through the said escutcheon or plate. The inner end of the head sleeve 54 projects 25 30 inwardly some distance from the escutcheon or plate 53 and is formed with a slot 57 in which the crank end 58 of a crank arm 59 is pivotally held, the said crank arm at its free end being bent to provide a support for 35 an angularly disposed handle 60 and a finger-engaging lip or flange 61. When not in use the crank arm 59 together with the handle 60 is adapted to be turned and inserted 40 through a slot 62 formed in the escutcheon or plate 53, as shown by dotted lines in Fig. 5, the said handle 60 projecting inwardly through the strip 52 or through the part of the base or casement frame adjacent to the slot 62 in the escutcheon or 45 50 55 60 65 plate 53. As shown by full and dotted lines in Fig. 5, the crank arm 59 with its handle 60 may be either turned out or disengaged from the escutcheon or plate 53 for rotating the rod or shaft 16 and the worm or worm head 15 to operate the quadrant 14 and thereby move the sash, or the said crank arm and its handle may be turned into engagement with the escutcheon or plate 53 as shown by dotted lines in Fig. 5, to reduce 70 75 80 85 90 95 100 105 110 115 120 125 130 the projection of the said crank arm when not in use. Owing to the worm gear construction, the shaft 16 is automatically locked at all times, except when manually operated. The finger-engaging lip or flange 61 provides means for readily pulling the crank arm 59 and the handle 60 inwardly for disposition of these parts as shown in full lines in Fig. 5.

The sash attaching or engaging member 13 is formed with an offset or is stepped

up, as at 63, to give this member such contour at its intermediate portion as to extend over and interfit with relation to the table 23 of the member 12, the stepped offset or stepped up portion 63 of the member 13 having a depending socket 64, to fit over the upper end of the fulcrum stud 24 and bear on the ball 26, as shown by Fig. 2. The one side closure flange 63^a of the stepped up portion or offset 63 engages the end edge 70 75 80 85 90 95 100 105 110 115 120 125 130 of the cover plate 21 as at 21^a to limit the opening movement of the sash engaging member 13. The lower part of the sash attaching or engaging member 13 extends outwardly in the form of an arm 65 with which the outer terminal of the quadrant is connected or joined, the quadrant being further reinforced and sustained in rigid connection with the member 13 by a single arm 66 between the arm 65 and the base of the offset or stepped up portion 63 and the quadrant near the inner end of the latter. By this mode of attachment the quadrant 14 is given a clear projection for operation and at the same time is reliably and durably held associated with the member 13. From the upper part of the offset or stepped up portion 63 the member 13 continues in the form of an arm 67, the said latter arm at the outer side and the arm 65 having upstanding apertured flanges 68 and 69 which serve as means for securing the sash to the member 13. The member 13 has a very easy pivotal movement on the member 12, particularly in view of the anti-frictional ball 26 fitted in the socket 25 of the pivot stud or fulcrum post 24, and when the device has been operated to its maximum extent, the sash will be obstructed against further turning movement by engagement with a portion of the member 13 with the stop shoulder 28, so as to always hold the quadrant 14 in mesh with the worm or worm head 15. When the quadrant 14 will have been operated to open the sash to the predetermined maximum extent, the said sash will stand in about the position shown by Fig. 1, and during the movement of the quadrant 14, it will be held beneath the cover or keeper plate 38 which projects thereover with a free sliding engagement relatively to the worm or worm head 15. As hereinbefore indicated, the parts of the member 12 are so constructed that when applied in operative position to a sill and stool edge, there will be no open portions for the admission of water or moisture past the parts of the supporting base 12, and when moisture or water that does work back over the exposed portion of the supporting base 12 reaches the trough or receptacle 30, the same will be drained outwardly through the slot 32 over the securing member 29 and then onto the sill and finally flow off of the latter. All of the parts of this lower organization of the attachment

have been constructed for the best advantage in service as well as protection of the structural features of the frame.

The top hinge or pivotal organization introduced between the top of the sash and the bottom of the head 8 and comprising the hinge members 17 and 19 is reduced in vertical extent by making the said members as small vertically as possible. The member 17 has an upper edge rib 69^a extending almost fully along one side edge, fully over one end and part way over the remaining side edge, and the longer portion of the said rib 69^a angularly joins an upstanding flange 70 over the opposite end, and said flange 70 is similarly joined to flange 71 extending along the part of the side of the member towards the shorter side edge portion of the rib 69^a, an opening 72 being formed between the inner ends of the flange 71 and adjacent end of the rib 69^a of the side edge of the member 17 on which the flange 71 is located. The pivot stud or fulcrum post 18 rising from the member 17 stands opposite to the opening 72 and is surrounded by an arcuate guard 73 at a suitable distance therefrom and continuing from the inner part of the flange 71 over adjacent to the inner terminal of the rib 69^a on the same side edge portion of the member 17. The guard 73 is connected to a longitudinally straight guard or wall 74 extending completely towards and joined to the end flange 70, and by this means a moisture trough 74^a is provided, so as to take up and hold all moisture that may be driven between the members 17 and 19 during storms, and the moisture escapes or the water flows out from the trough or receptacle 74^a through an opening 75 formed in the lower part of the flange 71, as shown by Fig. 11. Between the part of the guard 73 which terminates adjacent to the inner terminal of the shorter side edge of the rib 69^a and the latter rib, a drain slot 76 is formed, so as to relieve the shallow trough or receptacle 17^a constructed between the longer and shorter portions of the rib 69^a at this part of the member 17 of collected moisture and cause a flow of the water outwardly towards the front of the frame, and by this means the entire upper auxiliary hinge connection forming part of the attachment is rendered water-tight, or will prevent the passage of water beyond a certain point, and what water does gather on the lower exposed portion or member 17 of the upper hinge organization will be free to be discharged outwardly and thereby obviate deterioration of the upper part of the frame. It is obvious that the member 19 which is secured to the lower portion of the head 8 will assist in forming a water-tight enclosure, especially when the socket or socket member 20 is in engagement with the pivot stud or fulcrum post 18, and the said socket member is given such contour as to move regularly within the space defined by guard 73 without liability of strain, in view of the fact that the member 17 will be obstructed in movement beyond a maximum predetermined movement in a manner similar to the check of the movement of the lower member 18 relatively to the member 12 when the sash will have been fully opened. The upper plate or hinge member 19 adjacent to the socket 20 is formed with a recess 77 one wall of which is adapted to contact with the inner terminal or shouldered edge 78 of the flange 71 of the member 17, the recess 77 being practically of V-shaped form and allowing sufficient clearance for the movement of the plate or member 17 on the upper rail of the sash, but checking the movement when the sash is fully open by engagement of the shoulder 78 of the member 17 with the inner reduced terminal of the said recess 77 of the plate or member 19. From the recess 77 of the plate or member 19 towards one end of the latter a side flange 79 is formed integral with the said plate or member 19, the width of the plate or member 19 from the socket 20 towards the opposite end of said plate or member being reduced and presenting an edge 80 of the thickness of the top 81 of the plate or member 19, the said edge 80 engaging the inner side of the flange 71 of the plate or member 17 and the flange 79 of the plate or member 19 closing over the side rib 69^a on the same side of the plate or member 17 as the flange 71 when the plate or member 17 and the sash is closed relatively to the plate or member 19. This provides for a neat outer appearance and compact closure of the two parts of the upper hinge organization, and the only opening exposed when the sash is closed will be the recess 77, the lower edge of the socket when the plates or members 17 and 19 are closed being located over the drain slot or outlet 76. In the base wall of the recess 77 adjacent to the shoulder 78, a further drain slot or drainway 78^a is formed to relieve said recess of all moisture that may collect therein. Consequently, when the members 17 and 19 are closed, moisture will be almost exclusively obstructed from entering between the two members, and what little moisture does enter or seep in between the two members will be taken up and held by the moisture receiving means and eventually run out or drain through the opening 75 in the flange 71 of the member 17 and through the drain slot 76. The moisture that may enter between the engaging portions of the two plates or members 17 and 19 at the lower edges of the wall of the recess 77 and of the socket 20 will be prevented from running in between the two members by the arcuate guard 73. The two plates or members 17

and 19 are adapted to be easily and readily secured in operative position, respectively, to the top of the sash and the lower portion of the frame head, and along the inner side 5 of the plate or member 19 is a flange 82 which snugly closes over the upper edge of the rib 69^a that joins with the flange 70 of the plate or member 17, so that a box-like association of the two plates or members 17 10 and 19 is provided when they are closed.

It is proposed to provide a lower sill and stool organization having the operating members 12 and 13 fitted thereto or mounted therein for ready application of the sill 15 and stool to the lower portion of a casement frame, to thereby facilitate installation of the improved attachment, it only being necessary to attach the lower portion of the sash to the member 13 and apply the upper 20 hinge members 17 and 19, respectively, to the upper rail of the sash and the lower part of the head of the frame. In preparing the sill and stool carrying the lower part of the attachment as just explained, the 25 several parts will be properly dimensioned in accordance with the frame to which they are to be applied, and by this means the casement window may be easily completed.

As hereinbefore indicated, very little cutting or boring of the parts of the sill and stool is necessary to receive the lower part of the attachment and likewise the upper parts of the frame and sash to receive the upper hinge plates or members 17 and 19. 30 The lower parts of the attachment, including essentially the members 12 and 13 and cooperating parts, are closely associated and have comparatively very little projection. The several parts of the attachment are also 35 constructed and may be associated for convenience in application and efficiency in operation as well as economy in cost of production and sale.

The operation of the improved attachment is very simple, and from the closed position of the sash shown by Fig. 2, the sash may be opened to assume the position illustrated by Figs. 1, 3, 5 and 6, the angular position of the sash when open being dependent upon the operation of the rod or shaft 16, worm or worm head 15 and quadrant 14. In view of the fact that the lower operating part of the attachment or member 13 carrying the quadrant 14 is applied to the lower rail of the sash and the member 12 40 mounted and secured in the sill and stool as hereinbefore explained and nearer one side of the sash and frame than the opposite side of the same, the greater portion of the sash 45 will be projected outwardly over the sill and beyond the outer side of the frame when the sash is open, and, hence, the operation of the sash may be practically effected without interfering with an inner screen 83, as

shown by Figs. 2 and 3, and therefore the 65 screen may remain closed during the operation or the opening and closing movements of the sash. The sash may also be turned at such angle by reverse operations of the rod or shaft 16, worm 15 and toothed quadrant 70 14 as to render both sides of the glass of the sash easily accessible for cleaning purposes from the interior of the frame, or without requiring such operation to be performed with inconvenience and danger to the operator. 75

What is claimed as new is:—

1. A casement window sash operating attachment comprising upper and lower members having a single fulcrum organization 80 disposed intermediately with relation to both members, the upper member being rotatable on the lower member and having a toothed quadrant projecting therefrom, a worm gear carried at one extremity of the lower member and operatively engaging the said quadrant, and means loosely engaging the worm gear for operating the latter. 85

2. A casement window sash operating means comprising upper and lower members having a single fulcrum organization disposed intermediately with relation thereto, the upper member being rotatable on the lower member and having a toothed quadrant extending therefrom, a worm gear loosely disposed at an angle of inclination 90 in the lower member and operatively engaging the quadrant, and means for operating the worm gear. 95

3. A casement window sash operating 100 means comprising upper and lower members having a single intermediate pivotal organization, the upper member being movable on the lower member and provided with a toothed quadrant, the lower member having a socket at one end, a worm gear loosely mounted and retained in the said socket and engaging the quadrant, and an operating shaft having one end loosely engaging the worm gear. 105

4. A casement window sash operating attachment comprising upper and lower members having a single intermediately located pivoting organization, the upper member having a toothed quadrant extending therefrom and the lower member provided with a socket at one extremity with an inner open wall, a keeper plate removably mounted in the socket to form a closure for the inner open wall thereof, a worm loosely mounted 110 in the socket and engaging the toothed quadrant, and an operating shaft extending through the keeper plate and loosely engaging the worm. 115

5. A casement window sash operating at 125 attachment comprising upper and lower members having a single intermediately located pivoting organization, the upper member

being movable on the lower member and having a toothed quadrant projecting therefrom and the lower member having a socket at one extremity thereof, a worm loosely mounted in the said socket to engage with and operate said quadrant and provided with an angular socket opening therein, and

an operating shaft having an angular head to loosely and separably engage the angular socket opening of the worm.

In testimony whereof I have hereunto set my hand.

ALBERT H. CARRIER.
